CONTAINER

Original Filed May 18, 1928

INVENTOR
A. B. FUHR
Munn & Co.
ATTORNEYS

UNITED STATES PATENT OFFICE

ALBERT B. FUHR, OF MACOMB, ILLINOIS

CONTAINER

Application filed May 18, 1928, Serial No. 278,727. Renewed June 22, 1931.

My invention relates to improvements in containers, and it consists in the combinations, constructions, and arrangements herein described and claimed.

5 An object of my invention is to provide a container which may be used for various purposes, but which is especially adapted to receive ashes drawn from a furnace, and to conceal the ashes in such a manner that the es-
10 capement of the ash dust, if any, will be directed back into the furnace.

A further object of my invention is to pro-
vide a device of the type described which has
15 novel means for retaining the ashes or con-
tents so that they cannot readily move there-
from and so that the device may be filled to a
greater degree.

A further object of my invention is to pro-
vide a device of the type described which may
20 be suspended from a wall or stood upon a
support and be used as a waste container.

Other objects and advantages will appear
in the following specification, and the novel
25 features of the invention will be particularly
pointed out in the appended claims.

My invention is illustrated in the accom-
panying drawings, forming part of this ap-
plication, in which

Figure 1 is a perspective view of my de-
30 vice,

Figure 2 is a longitudinal sectional view
of my device as applied to the ash door of
a heater, and

Figure 3 is a modified form of my device.

35 In carrying out my invention, I provide
a body portion 1 having a front wall 2,
side walls 3 and 4, and a rear or back wall
5. The walls 2 to 5, inclusive, are connected
at one end by means of a flat bottom por-
40 tion 6.

The front wall 2 is shorter in length than
the rear wall 5. The edges of the side walls
45 adjacent the front wall 2 extend a short dis-
tance or to points indicated at 7 from the
front wall. The side walls 3 and 4 have
their ends tapering from the point 7 to the
edge of the back wall 5.

Retaining members 8 extend inwardly
50 from the back wall 5 for a purpose herein-
after described. The retaining members 8

extend transversely from the points 9 adja-
cent the ends of the side walls 3 and 4 to
points a short distance from the center of
the top edge of the back wall 5.

55 A handle 9 is provided for the body por-
tion 1 and is pivotally mounted at 10 to
the side walls 3 and 4.

From the foregoing description of the va-
rious parts of the device, the operation there-
of may be readily understood. The body 60
portion 1 may be disposed in a substantially
horizontal position whereby the back wall 5
will rest upon the base 11 of a furnace or
heater and extend slightly into the opening
12 for the ash door. The open end of the
65 body portion 1 will therefore be in substan-
tial alignment with the door opening 12,
and the closed end, that end at the bottom
portion 6, will rest upon the floor. While
in this position the user may readily draw
70 the ashes from the heater and into the body
portion.

The ashes from the heater may be drawn
into the body portion where they will pass
75 to the bottom thereof and gradually fill the
body portion. The retaining members 8 and
the extensions of the side walls 3 and 4 aid
the operator in filling the body portion 1
to its greatest capacity.

The body portion 1 may then be lifted to 80
its vertical position, where it will rest upon
the bottom 6 and then conveyed to any de-
sired location by the aid of the handle 9
and emptied. The retaining members 8 and
the extensions of the side walls 3 and 4 also 85
enable the container to be moved back into
engagement with the opening 12 of the heater
after it has been partially filled without
spilling any of the contents thereof.

90 In Figure 3 I have shown a modified form
of my device and identical in construction
to the form shown in Figures 1 and 2 with
the exception of a curved-over portion 13
which is integral with the back wall 5 and
which is adapted to receive the lower edge 95
of the opening 12 of the heater so as to firmly
hold the body portion against displacement
while the ashes are being drawn from the
heater. Furthermore, the extensions of the
side walls 3 and 4 may be bent inwardly so 100

as to provide reinforcing strips as indicated at 14.

I claim:

- 5 1. A device of the type described comprising a body portion having a front wall, a back wall, side walls, and a flat bottom portion connecting said walls, said front wall being shorter in length than said back wall, an end of each side wall being tapered from the edge of the back wall, and retaining strips secured to the side walls and the back wall, said retaining strips being spaced apart from one another to provide an opening therebetween.
- 10 15 2. A device of the type described comprising a body portion having a front wall, a back wall, side walls, and a flat bottom portion connecting said walls, said front wall being shorter in length than said back wall, an end of each side wall being tapered from the edge of the back wall, retaining strips secured to the side walls and the back wall, said retaining strips being spaced apart from one another to provide an opening therebetween, and an integral hooklike extension carried by said back wall and extending substantially the width of said opening.

Signed at Macomb, in the county of McDonough and State of Illinois, this 14th

35 day of May, A. D. 1928.

ALBERT B. FUHR.
